TOOL.

Specification of Letters Patent. Patented June 26, 1917.

Application filed January 5, 1917. Serial No. 140,818.

To all whom it may concern:

Be it known that I, WILLIAM L. MILLIORN, a citizen of the United States, residing at El Paso, in the county of El Paso and State of Texas, have invented new and useful Improvements in Tools, of which the following is a specification.

The present invention relates to improvements in tools, and has for its object to combine a number of implements in one compact, simple and easily operated structure.

With the above and other objects in view the improvement resides in the construction, combination and arrangement of parts set forth in the following specification and falling within the scope of the appended claims.

In the drawings:

Figure 1 is a side elevation of a tool constructed in accordance with the present invention,

Fig. 2 is a similar view showing the tool in its open or spread condition,

Fig. 3 is a plan view of the same,

Fig. 4 is a longitudinal sectional view approximately on the line 4-4 of Fig. 3,

Fig. 5 is a sectional view approximately on the line 5-5 of Fig. 1,

Fig. 6 is a sectional view approximately on the line 6-6 of Fig. 1,

Fig. 7 is a sectional view approximately on the line 7-7 of Fig. 1,

Fig. 8 is a perspective view of a spool holder member,

Fig. 9 is a perspective view of the brake member for said spool, and

Fig. 10 is an enlarged elevation of the wire clutch or dog and the roller associated therewith, the cover plate for the same being removed.

The tool is especially designed for domestic use and for farmers and others engaged in the construction of wire fences, as it combines all the requisites necessary for such work, providing a tool in which a strand of wire is arranged having means for twisting the said wire around the line wires of a fence, or when the wire is to be used for other purposes, as well as means for cutting the wire. The tool also embodies a wrench member, pliers, nail extracting means, a punch, a screw driver and nipping jaws which may be also employed for twisting the wire carried by the tool.

Referring now to the drawings in detail the numeral 1 designates a hatchet or ax blade having one of its edges notched, as at

2, to provide means for extracting headed nails. The blade 1 has its head of a rounded formation and is depressed at its said head from one of the sides thereof, the flange or angular wall formed by the said depression being rounded to conform with the periphery of the said head, and the head, upon its outer edge, is formed with a curved jaw 3. Integrally formed with the head of the jaw 3 is a longitudinally extending handle 4, the same having its end beveled and if desired sharpened to provide a screw driver or chisel. The handle 4 upon its outer edge and at a suitable distance adjacent to the head thereof is provided with an offset element 5 that is adapted to serve as a punch, and which is indicated by the numeral 6.

Pivotedly secured in the referred to depression of the head of the blade 1, as at 7, is the rounded portion or head 8 of the second member of the device, the said head 8 being formed upon its outer edge with a curved jaw 9 which is adapted to co-act with the jaw 3 of the blade 1. The head 8, upon the outer edge thereof, but inward of the jaw 9, is provided with an angular extension forming a poll or hammer head 10, and the inner edge of the said poll 10 is provided with transverse teeth 11. The poll 10 is formed by notching the outer edge of the head 8, the inner wall 13 of the said notch being disposed angularly with relation to the inner side or wall of the poll 10, and arranged upon the said angular wall 13 is a block 14, the same having its outer face formed with transverse teeth that are disposed to co-operate with the teeth 11 to engage with a suitable obstacle therebetween and thus forming a wrench. The block 14 has pivotally secured to the sides thereof link members 15, the said links being also pivotally connected to the sides of the head 8, and upon the inner wall provided by the depression between the poll and the angular wall 13 is disposed a flat spring 16 that has its free end exerting a pressure upon the inner end of the block 14 to normally force the said block to contact with the angular wall 13. Extending longitudinally from the head is the handle portion 17, the outer end of the same being hollow and tubular, but the portion thereof at its juncture with the head 8 is solid and has its outer wall preferably inclined to the said tubular portion, and the said inclined outer wall is notched, as at 18, to provide a socket member to en-

gage with a nut or the head of a bolt. The solid portion 12 of the handle is also formed with a substantially cone-shaped opening 18, the reduced portion of which receiving the 5 punch 6 of the handle 4 of the blade 1, and by flaring the opening 18 it will be noted that the material severed by the punch 6 will find a free outlet through the said opening. The solid portion 12 of the handle 17 between the jaw and the referred to opening 10 18 is formed with depending transverse teeth 19 which are adapted to co-engage with similar teeth 19 upon the handle 4 forming pincers or pliers, while the rounded walls 15 of the heads of the device are provided with notches 20 and 21 respectively which are normally disposed out of alinement and preferably two of the walls provided by the said notches are sharpened, whereby when the 20 handles are manipulated to bring the notches into alinement, the said sharpened walls provide cutting means for wire or the like.

Adapted to be received in the end of the hollow tubular handle 17 and to preferably 25 engage therewith is the rounded shank 32 of what I will term a holder member 32. This member, at the outer end thereof is bifurcated or provided with laterally extending spaced arms 31-31, each of the 30 said arms being provided with alining openings. The arms 31 may be in the nature of spring members, and the openings 31' therein are adapted to receive a shaft or trunnion 30 arranged centrally of a spool 29, 35 the said spool having wound thereon a wire 33. This wire is adapted to be drawn longitudinally of the handle 17 over a guide roller 35 that is pivotally secured to the head 8. Also pivotally secured to the head 8 or more 40 particularly speaking to the poll 10, as at 36', is a dog 36 that has its toothed or engaging surface 36^a disposed opposite the roller 35 to force the strand of wire 33 against the said roller 35. It will be noted, 45 especially by reference to Fig. 10 of the drawings, that the dog 36 is pivotally secured angularly with respect to the roller 35, so that the wire will be permitted to move outwardly, but will be prevented from movement inwardly or in the direction of the 50 spool 29. The member 36 is centrally provided with an elongated slot 36^b which is struck concentrically from the pivot 36' and within which is arranged a compression 55 spring 36^c, while the numeral 36^d indicates a stud which is formed upon the head 8 and which projects within the slot 36^b, the spring 36^c exerting a pressure between one of the 60 end walls provided by the slot 36^b and the stud 36^d, to normally bring the engaging or toothed surface 36^a of the dog 36 into proper position with relation to the strand of wire 33 and the roller 35. The dog 36 as well as the roller 35 have arranged thereover a close- 65 sure plate 36^e.

In order to prevent the free turning of the spool upon the member 32, I provide a braking means which is preferably in the nature of a spring member shaped to include a rounded end 26 which is arranged over the 70 spool and which is adapted to be brought into frictional contact with the spool, the pressure of the said contact being regulated in a manner which will presently be described. Formed with the rounded end 26 75 is the angular body portion 25 of the device, and extending from the said angular portion 25 is a straight portion 25' that terminates in spaced angular lugs 24, and these lugs are adapted to be received in suitable depressions in the hollow handle 17, while the strand of the wire 33 is designed to pass between the said lugs. In order to facilitate the free passage of the said strand of wire, the straight portion 25 between the angular 80 portions or lugs 24 at the end thereof is rounded or bulged outwardly, as at 25^a, for the length of the said straight portion 25'. In order to secure the brake member upon the handle 17 and also to regulate the tension with which the rounded end 25 thereof 90 engages with the spool, I arrange upon the said handle 25 a sleeve 27 which overlies the straight portion 25' of the brake device and which being slidable upon the handle, may 95 be brought to engage with the annular portion 25 of the said brake so as to force the rounded portion 26 thereof into frictional contact with the spool 29 or, of course, when the sleeve 27 is moved in an opposite direction or toward the head of the device, the rounded portion of the brake may be permitted to swing away from the spool, as shown by both the full and dotted lines in Fig. 1 of the drawings. The hollow portion 105 17 of the handle may be employed as a compartment for suitable articles to be used with the tool, such as brads, staples or similar devices.

The sleeve 27 preferably has its bore 110 flared at the end thereof disposed adjacent to the angular portion 25 of the brake member, so that a comparatively slight longitudinal movement of the sleeve in the direction of the brake will result in forcing 115 the rounded end of the brake into tight engagement with the periphery of the spool.

Having thus described the invention, what I claim is:

1. In a combination tool, substantially as 120 herein described, two pivoted members, one including a hollow handle, of a spool having wire wound therearound, a holder member for the spool received within and closing the outer end of the hollow handle, guide 125 means for the wire, means for preventing the movement of the wire in one direction, and brake means for the spool.

2. In a combination tool, including two 130 pivoted members, each provided with co-

acting jaws and each provided with handles, one of said handles being hollow, of a wire carrying spool having trunnions, a support for the spool upon which the trunnions are journaled, said support frictionally engaging in and closing the end of the hollow handle, a roller at one end of the tool over which the wire is guided, a spring pressed member disposed opposite the roller and contacting with the wire for holding the wire against movement in one direction, a brake for the spool, and operating means for the brake.

3. In combination with a tool, substantially as herein described, comprising two pivoted members each provided with a co-acting jaw and each provided with a longitudinally extending member comprising a handle, one of said handles having an opening from one end thereof, of a wire carrying spool having its sides provided with trunnions, a holder member having a forked end provided with openings forming journal bearings for the trunnions, said holder member adapted to be inserted in the open end of the handle to close the same, a roller at the end of the tool and adjacent one of the jaws providing a guide for the wire, a spring pressed dog arranged opposite the roller and contacting with the wire to hold the same against movement in one direction, a brake for the spool including a spring body having a rounded end to engage with the spool, said body having its opposite end connected with the handle, a longitudinally movable member having a flared bore upon the handle and receiving the spring body of the brake, whereby to engage with and compress the body to force the curved end of the brake to contact with the periphery of the spool or to permit of said end springing away from such engagement with the spool.

4. A tool of the class described including a head and handle, a spool having wire wound thereon journaled in bearings at the end of the handle, brake means arranged upon the handle and adapted to engage with the spool to regulate the rotary movement of the spool, a roller journaled upon the head adapted to receive the end of the wire strand upon the spool, a dog pivoted to the head opposite and to one side of the roller, said dog having one of its ends formed with teeth designed to engage with the wire to force the same against the roller, said dog having its body slotted, a stud upon the head passing through the slot to limit the swinging movement of the dog in the direction of the roller, and a spring member also within the slot and exerting a tension between one of the end walls of the slot and said stud for moving the dog to bring the toothed portion thereof in the direction of the roller.

In testimony whereof I affix my signature.

WILLIAM L. MILLIORN.
